UNITED STATES PATENT OFFICE.

ELIPHALET C. NORTON, OF BELVIDERE, ILL., ASSIGNOR OF ONE-HALF TO
ALBERT WRATE, HENRY LIST, AND SAMUEL WYLDE, OF SAME PLACE.

HAY-CARRIER.

SPECIFICATION forming part of Letters Patent No. 309,157, dated December 9, 1884.

Application filed April 9, 1884. (No model.)

To all whom it may concern:

Be it known that I, ELIPHALET C. NORTON, a citizen of the United States, residing in Belvidere, in the county of Boone and State 5 of Illinois, have invented a new and useful Hay-Carrier, of which the following is a specification.

This invention relates to a class of devices employed mainly in connection with power-forks to unload hay from the wagon and 10 deliver it in the place of deposit.

It consists in a carrier mounted to move freely on a suspended way, and is provided with a combined automatic carriage-detent 15 and tripping mechanism, and a combined automatic rope-detent and tripping mechanism. These devices in their construction and arrangement, and their several combinations with the necessary parts to produce a complete 20 carrier, all of which will be hereinafter more fully described, constitute the subject-matter of this specification.

In the accompanying drawings, Figure 1 is an isometrical representation of a hay-carrier 25 embodying my invention. Fig. 2 is a side elevation. Fig. 3 is also a side elevation, in which a portion of the carriage is omitted to more clearly show the construction; and Fig. 4 is a transverse vertical section on dotted line 30 X on Fig. 2.

The vehicle of my improved carrier is composed of cast and wrought material, and the like sides of the frame, consisting of the vertical portions A and the horizontal portions 35 B, are produced in right-angle form. The end portions of the vertical sides are provided with uprising portions a, of ear form, fitted with stud-journals b, projecting from their inner faces.

At C are represented traveling wheels 40 mounted to revolve on the stud-journals b. The side plates, A, are provided at their forward ends with pendent portions c, and one of these pendants is provided with a tubular 45 stud-journal, d, projecting from its inner face, and is fitted to receive a screw-bolt, e, which is passed through the pendent portions c and through the tubular stud-journal d, and serves to fix this forward end of the plates to each

other. The rear ends of the side plates, A, are 50 provided with pendants h, and one of these pendants is provided with a tubular stud-journal, h', projecting from its inner face, in every particular substantially the same as the tubular stud-journal d, and is fitted to receive 55 a screw-bolt, i, which is passed through the pendants h and through the tubular stud-journal h', and serves to fix this rear end of the plates to each other, producing a carriage of a suitable construction to receive a suitable 60 way-beam, D.

At E is represented a sheave of pulley form, having its periphery grooved to receive a rope. This sheave E is supported upon the tubular journal h' between the pendants h at the rear 65 end of the carriage, to revolve on its journal-support between the pendants.

At F is represented an automatic operating rope-detent of lever form, having a pivotal support on the tubular stud-journal d between 70 the pendants c at the forward end of the carriage. The rear end, k, of this rope-detent F is fitted in jaw form, having its under face serrated or provided with teeth to engage the rope upon the sheave E, as shown in Fig. 3, 75 to prevent the rope running from the sheave. The forward end, l, of this rope-detent F is produced in a downward-curving form to override a trip stop-block, m, fixed to the under face of the way-beam D in such a manner as 80 to disengage the detent from the rope, as shown in Fig. 2.

At n is represented a link pivoted in the lever-detent F at a point rearward of its pivotal connection with the carriage in such a 85 manner that a weight upon the link, or on a rope, L, connected with the link, will operate to hold the detent-jaw k in contact with the rope on the pulley.

At H is represented an automatic operating carriage-detent of lever form, provided with a weight, o, at its rear end, and having a pivotal support on the tubular stud-journal d between the pendants c at the forward end 90 of the carriage. The forward end of this carriage-detent is produced in down-curving latch form to override the trip stop-block m, and its hook-latch p, by means of its weighted

rear end, will engage the block m , to hold the carriage in connection therewith in a detachable manner.

At I is represented a sheave provided with 5 a depending swivel-hook, s , to receive a suitable power hay-fork, a portion of which is shown at K .

At L is represented a hoisting-rope having one end, as at t , fixed to the link n , pivoted 10 in the rope-detent. This hoisting-rope L from its connection with the link n passes under the fork-sheave I , thence over the sheave E in the rear end of the carriage, from which its free end N extends to connect with the 15 power employed to operate the mechanism.

In the use of my improved carrier the way-beam D is suspended to any suitable support by means of suspension-rods P extending centrally through the way-beam. This way-beam 20 is preferably inclined in such a manner as to cause the carriage to gravitate toward the trip stop-block m , which is placed vertically over or as nearly over the hay to be elevated and carried as may be convenient. When the carrier has descended the inclined way-beam to engage the trip-stop, the carriage-detent, by 25 means of its down-curving hook-latch and weighted construction, will engage the trip-stop and hold the carriage in position on the way-beam, and the rope-detent, by means of 30 its curved forward end overriding the trip-stop, will be disengaged from the rope and permit the fork to descend, as represented in Fig. 1, to be fixed in the hay to be elevated. When 35 the fork is elevated, the fork-sheave I will engage the weight o of the carriage-detent and disengage its hook-latch from the stop, as shown in the dotted lines in Fig. 2, and permit the carriage to ascend the inclined way-beam. This movement of the carriage on the 40

way-beam will disengage the rope-detent from the trip-stop, and the weight of the loaded fork upon the hoisting-rope will cause the foot of the rope-detent to engage the hoisting-rope on the sheave E , and prevent it running 45 from the sheave and hold the loaded fork elevated, as represented in Fig. 3. The continued draft upon the draft branch N of the hoisting-rope will cause the carriage, with the loaded fork, to ascend the inclined way until it reaches 50 the place of deposit, when by means of a trip-rope connected with the fork the hay is dropped from the fork. When the fork is unloaded, the tension on the draft branch N of the hoisting-rope will relax and permit the 55 carriage to descend the inclined way-beam to engage the trip-stop, disengage the rope-detent, and permit the fork to descend, to be again loaded.

I claim as my invention— 60

1. The herein-described carriage, consisting of the like sides composed of the vertical and horizontal portions, the travelers to engage the upper surface of the way-beam, and tubular stud-journals to receive the sheave and detents, and connecting-bolts, substantially as 65 and for the purpose set forth.

2. The combination, with a trip-stop, of the two-part carriage formed with tubular stud-journals, as described, a lever-latch detent to 70 engage said stop, a rope-detent to engage the hoisting-rope, said detents being pivoted upon one of the stud-journals of the carriage, and a fork-supporting sheave for disengaging the lever-latch detent, substantially as set forth.

ELIPHALET C. NORTON.
